UNITED STATES PATENT OFFICE.

JULIUS J. MILLER, OF ST. JOSEPH, MICHIGAN, ASSIGNOR TO WILLIAM P. HEALY, OF CHICAGO, ILLINOIS.

MACHINE FOR MAKING WIRE-BOUND SHIPPING-RECEPTACLES.

1,110,073.

Specification of Letters Patent. Patented Sept. 8, 1914.

Application filed July 5, 1912. Serial No. 707,766.

To all whom it may concern:

Be it known that I, JULIUS J. MILLER, a citizen of the United States of America, and resident of St. Joseph, Berrien county, Michigan, have invented a certain new and useful Improvement in Machines for Making Wire-Bound Shipping-Receptacles, of which the following is a specification.

My invention relates to machinery for making receptacles in general, but more particularly to machines for applying reinforcing or binding members to the side walls of receptacles of this kind, and especially machines of this character having provisions for stapling the binding wires to the outer surface of the box or crate or other receptacle.

Generally stated, the object of my invention is to provide a novel and improved machine of the foregoing general character.

A special object is to provide a machine which will fasten the binding wires or other similar reinforcing members in place at the same time that the head or end wall of the box or crate or other receptacle is secured to the side walls thereof, and having means for automatically rotating the materials during the process of constructing the box or crate or other receptacle, preferably about a fixed axis, whereby the fasteners, such as staples, are successively inserted circumferentially thereof.

Another object is to provide a machine of this kind in which means are provided for securing one or more binding wires or other flexible reinforcing members around the box or crate or other receptacle at a point or points between the ends thereof, the mechanism for so doing being preferably disposed in position to operate upon the materials in advance of the staplers by which the side walls, such as strips of veneer, are secured to the head or end wall of the box or crate or other receptacle, or to both heads or end walls thereof, depending upon the character of the receptacle being made.

Another object is to provide a machine of this kind which will make a round box or crate or other receptacle to which the binding wires or other reinforcing members are applied and secured in place at the same time that the side walls are secured to the head or end wall thereof, or to both heads or end walls, depending upon the character

of the receptacle, as will hereinafter more fully appear.

It is also an object to provide certain details and novel features of construction tending to increase the general efficiency and serviceability of a wire bound box or crate or barrel machine of this particular character.

To the foregoing and other useful ends, my invention consists in matters hereinafter set forth and claimed:

In the accompanying drawings, figure 1 is a side elevation of a machine embodying the principles of my invention. Fig. 2 is a perspective of the wire bound box or receptacle blank made by the said machine, and which blank is then fastened by this same machine to the head or end wall of the receptacle, or to both heads or end walls thereof, it being understood, however, that the two marginal binding members are not applied at the time that the blank is formed by the stapling of the two intermediate binding wires to the strips of veneer, these marginal binding members being secured in place at the same time that the said strips of veneer are stapled or fastened to the heads or end walls of the boxes or crates or other receptacles of this general character. Fig. 3 is a plan of the machine shown in Fig. 1. Fig. 4 is a longitudinal section of the said machine on line 4-4 in Fig. 3. Fig. 5 is a front elevation of the said machine. Fig. 6 is a detail sectional view of one of the rotating supports or workholders which engage the heads or ends of the box or crate or other receptacle during the operation of stapling the materials together. Fig. 7 is a perspective of one of the heads or end walls of the round box or crate or receptacle. Fig. 8 is a perspective of the finished receptacle.

As thus illustrated, my invention comprises a base A upon which are mounted the front and rear upright castings B and C for supporting the various operative parts in suitably elevated positions. The castings B are connected by a shaft b upon which are mounted the sprockets b¹, said shaft extending transversely of the machine. The castings C are connected by a shaft c upon which are mounted the sprockets c¹, the said shaft being disposed transversely of the machine in the plane of the first men-

tioned shaft. The two shafts are connected by the sprocket chains D which are arranged on the said sprocket wheels and adapted to form an endless traveling workholder. The castings C are also connected by the usual stationary crosshead E and the vertically movable or reciprocating crosshead F, the staplers G being mounted upon said crossheads in the usual manner, and being of any suitable, known or approved construction.

The intermediate staplers H are of similar character and mode of operation, but are disposed in advance of the staplers G, whereby the staples driven by the staplers H are inserted in the materials at a point over the traveling workholder formed by the chains or link belts D, it being observed, however, that all four staplers are operated simultaneously by the up and down movement of the crosshead F, which latter is operated in any suitable manner. For example, said crosshead F may be connected by the pitmen f with the eccentrics f¹ mounted on the ends of the drive shaft I, which extends transversely of the machine at a point below the said staplers. Each stapler is, of course, provided with a suitable device for feeding the staple wire thereto, and the staplers G are arranged to receive the binding wires from the reels J at the top of the machine. In a similar manner the staplers H are arranged to receive the binding wires from the reels K at the top of the machine. Thus each stapler is adapted to insert each staple crosswise of a binding wire to secure the latter in place upon the outer surface of the side walls of the box or crate or other receptacle.

If desired, as shown in Fig. 2, the reels J can be arranged to feed flat metal strips in place of the binding wires, or if desired flat strips of wood can be employed as a substitute, whereby the end of the box or crate or other receptacle will be bound around on the outside with flat hoops.

The strips of veneer forming the side walls of the receptacle can be laid upon the traveling workholder D by hand. As a matter of further and special improvement, however, these strips are fed from a hopper L disposed immediately in front of the staplers H, the said traveling workholder being provided with lugs d which engage the edge of the strip of veneer at the bottom of the hopper and remove it therefrom in the direction of the staplers, the strips of veneer dropping automatically into the spaces between the said lugs as the workholder travels along. The said hopper is preferably supported by brackets l secured to the castings C at the rear end of the machine.

The means for supporting and rotating the materials during the operation of securing the heads 1, shown in Fig. 7, to the strips

of veneer 2, are as follows: A short shaft M is disposed transversely of the machine, at each side thereof, so as to rotate about an axis which is directly below the staple drivers of the staplers G, each said shaft being mounted in one of the upright castings C of the frame or body of the machine. Each shaft is provided with a sleeve m connected therewith by a spline or feather, whereby each sleeve is movable endwise relative to its allotted shaft. The inner end of each sleeve m is provided with a disk or annular member m¹ having teeth m² on the inner surface thereof. Each sleeve is also provided with a grooved collar m³, and these collars are engaged by the fork shaped ends of the bell crank levers m⁴ and m⁵, said levers being pivoted at m⁶ and m⁷ upon the brackets m⁸ secured to the inner sides of the said body frame. A foot lever m⁹ is arranged transversely of the machine, being pivoted at one end thereof, and the two bell cranks are connected by links m¹⁰ and m¹¹ with the said foot lever or treadle. With this arrangement, a depression of the said foot lever or treadle operates to throw the two disks m¹ toward each other, and the mechanism can be held in this position by a catch m¹² for engaging the said foot lever or treadle. When the said foot lever or treadle is released, the springs m¹³ and m¹⁴, which are applied to the said bell cranks, then serve to automatically separate the two disks m¹—that is to say, serve to move these disks away from each other to release the finished box or crate or other receptacle. The end walls or heads 1 of the box or crates are placed upon these disks m¹, so that the teeth m² impinge upon the depressed or countersunk surface of each head or end wall; and in this way the hoop or annular portion of each head or end wall is supported upon the periphery of the disks m¹, whereby the latter serves to securely support the head or end wall below one of the staplers G and in position to receive the staples. The shafts M are provided at their outer end with ratchet wheels m¹⁵ which are engaged by the pawls or ratchet dogs m¹⁶ on the swinging arms m¹⁷, which latter swing about an axis coincident with the axis of the said shafts and ratchet wheels. These arms m¹⁷ are connected by pitmen m¹⁸ with the eccentrics m¹⁹ on the shaft I, whereby the disks m¹ are intermittently rotated and the work given a step by step rotary feed motion during the stapling operation. The traveling workholder D is operated by a similar ratchet feed device N applied to the shaft e and operated by a pitman n, the said pitman being in turn actuated by an eccentric n¹ on the said driving shaft. It will be understood that the ratchet feed devices thus provided for the traveling workholder and the rotary workholders are operated simultaneously

and in such manner that the materials are properly fed along in a step by step manner during the operation of the machine.

The mode of operation is as follows: 5 When the materials are in position, the machine is started and the intermediate binding wires 3 are secured in place by the staplers H, thus forming a continuous blank which is fed in a step by step manner to 10 the rotary workholder. The ends of the strips of veneer 2 and the binding members 4, which latter may be of any suitable character, are then secured to the hoops or heads of the end walls 1 by the staplers G, and 15 after both heads or end walls are in place, the machine is stopped before the disks m^1 have been given a complete rotation, in order to leave the receptacle open at one side thereof. However, and if it be desired to 20 make a receptacle which is closed all around and simply left open at one end thereof, then a hoop is placed on one of the disks m^1 , similar to the hoops of the end walls, and a complete end wall is then placed upon 25 the other disk m^1 , whereby a round receptacle is made having a closed bottom and an open top—that is to say, one end is closed but the other is left open and simply provided with an inner rim or hoop to which a 30 sheet of veneer or a board may be secured afterward, when it is desired to close or seal the receptacle. Thus it will be seen that the strips of veneer and marginal binding members are secured together at the same 35 time that the side walls are secured to the outer edges of the heads or end walls of the receptacle.

From the foregoing it will be seen that by my invention I provide a machine capable of producing a round box or crate, or other receptacle, such as a barrel or banana crate, and which secures the heads of the end walls and the binding members in place by one and the same operation thereof.

45 What I claim as my invention is:

1. A machine for making wire bound shipping receptacles, comprising fastener

driving mechanism, instrumentalities for supplying binding wires to said mechanism, means for holding the materials in position to receive the fasteners, whereby each fastener secures a binding member and a head of the receptacle to the side walls thereof, and a device for causing the rotation of said means, whereby the side walls are successively received thereon, and to permit the successive insertion of fasteners circumferentially of said receptacle, said means being constructed to engage only the outside of the receptacle. 50

2. In a machine for making shipping receptacles, means for feeding slats or staves, means for feeding and fastening one or more binding members to said slats intermediate their ends, means beyond the said feeding means for winding the slats and binding member or members attached thereto, and means for feeding and fastening an outer binding member along the ends 65 of the slats while on said winding means. 70

3. In a machine for making shipping receptacles, means for feeding slats or staves, means for feeding and fastening one or more binding members to said slats intermediate their ends, means beyond the feeding means for winding the slats and binding member or members attached thereto, and means for feeding and fastening an outer binding member along the ends of the slats while on said winding means, said 75 winding means being provided with devices for holding end pieces within the receptacle while the same is being formed, these end pieces being held in position to be fastened within the receptacle by the same devices 80 that fasten the outer binding members to the slats. 85

Signed by me at St. Joseph, Michigan, this 26th day of June, 1912.

JULIUS J. MILLER.
